UNITED STATES PATENT OFFICE.

TOWNER K. WEBSTER, JR., OF EVANSTON, ILLINOIS, ASSIGNOR TO AMERICAN STEAM CONVEYOR CORPORATION, OF CHICAGO, ILLINOIS, A CORPORATION OF NEW YORK.

TANK FOR ASH-CONVEYER SYSTEMS.

1,313,436.

Specification of Letters Patent.

Patented Aug. 19, 1919.

Application filed August 23, 1917. Serial No. 187,776.

To all whom it may concern:

Be it known that I, TOWNER K. WEBSTER, Jr., a citizen of the United States, residing at Evanston, in the county of Cook 5 and State of Illinois, have invented a certain new and useful Improvement in Tanks for Ash-Conveyer Systems, of which the following is a full, clear, concise, and exact description, reference being had to the accompanying drawings, forming a part of 10 this specification.

My invention relates to ash conveyer systems, and more specifically to ash tanks arranged to receive ashes from a conveyer 15 conduit and located at a point of advantage so that the ashes may be loaded into a vehicle or disposed of in any other suitable manner.

It is one of the objects of the present 20 invention to provide an ash tank adapted for use in connection with a steam ash conveyer system which is efficient in its operation and which can be manufactured economically.

25 A further object of the present invention is the provision of apparatus for draining water from the contents of the tank so that the same readily may be discharged from the tank without sticking and clogging in the discharge gate or chute. Incidentally, 30 the removal of the water from the tank contents prevents freezing during the winter months.

35 A further object of the invention is the provision of an arrangement for agitating the ashes contained within the tank to feed the ashes to the discharge gate located at the lower end of the tank.

These and other objects of the present 40 invention will be pointed out more clearly in connection with the accompanying drawings, wherein,

Figure 1 is a vertical cross sectional view 45 of the ash tank of my invention;

Fig. 2 is a top view of Fig. 1;

Fig. 3 is a horizontal sectional view taken along the line 3—3 of Fig. 1 looking in the direction indicated by the arrow;

Fig. 4 is an enlarged detail cross sectional 50 view of the lower end of the tank showing the drain pipes and steam nozzle; and

Fig. 5 is a detail cross sectional view of the discharge gate employed at the lower end of the tank.

Similar characters of reference refer to 55 similar parts throughout the several views.

Referring first to Fig. 1, 6 designates a suitable support, preferably constructed of concrete, upon which is mounted an ash tank 7 substantially cylindrical in shape and preferably constructed of concrete. Leading into the upper end of the tank 7 is an ash conveyer conduit 8 which extends through a deflector plate 9 carried by the cover of the tank 10. Carried by the cover 10 and positioned opposite the discharge opening of the ash conveyer conduit 8 is a baffle plate 11 against which the ashes delivered by the conveyer conduit 8 are arranged to strike. A suitable vent is employed at 12 70 which affords communication between the interior of the tank and the atmosphere.

Located in the floor of the tank 7 and preferably centrally located with respect thereto is a discharge opening 14 provided with a gate 15. Mounted upon the floor of the tank and disposed around the discharge opening 14 is an annular steam nozzle pipe 16 provided with a plurality of openings 17—17 arranged to project steam into the 80 tank. The annular steam nozzle pipe 16 communicates with a steam supply pipe 18 extending outwardly from the tank and leading to a suitable steam supply. The interior of the discharge opening pipe 14 also 85 communicates with the steam supply pipe shown at 18' and is arranged to receive steam from the pipe for the purpose hereinafter pointed out. Carried upon the floor of the tank 7 and disposed around the steam 90 nozzle 16 is a plurality of drain pipes 19—19 which communicate with one another, as shown at 20—20 in Fig. 3, and lead to the atmosphere as shown at 21 in Fig. 4. These drain pipes are made of porous material, and preferably constructed in sections, as 95 illustrated. The end of the drain pipe 21 leading to the atmosphere is connected with the steam supply pipe 18 through a manually operable valve shown at 22.

The operation of the device is as follows: The ashes are conveyed from their source, which may be a boiler room or a locomotive ash pit, through the pipe 8 by means of steam. As the ashes are projected through the conveyer conduit 8 they strike the baffle plate 11 and fall downwardly to the lower 150 end of the tank. Some of the steam escapes

through the vent 12 while the remainder condenses and trickles to the bottom of the tank in the form of water. When the water reaches the drain pipes 19 it seeps through 5 the porous material and passes out of the tank through the end 21 of the drain pipe. When it is desired to remove the ashes from the tank the gates 15 are opened and most of the ashes within the tank 7 permitted to 10 pass downwardly through the discharge opening. There is, however, a certain amount of ashes left within the tank, as shown in Fig. 1. Steam is then projected through the pipe 18 and through the openings 17-17 in the annular pipe 16 against the remaining ashes with the result that the ashes are removed to the extent shown by 15 the dotted lines in Fig. 1. Some of the steam projected through the nozzle passes through the vent opening 12 while the remainder condenses and escapes through the drain 20 pipes 19.

Because of the provision of the drain pipes, the tank contents and more particularly the ashes adjacent the discharge chute are kept comparatively free from moisture with the result that they flow freely from the tank without sticking or clogging when the discharge gate is opened. In the event 25

of freezing within the discharge pipe 14 30 steam is admitted through the steam supply conduit 18'. In case the water freezes at the point of its discharge from the drain pipes 19 the valve shown at 22 is opened.

Having thus described my invention what 35 I claim as new and desire to secure by Letters Patent of the United States is:

1. An ash conveyer system comprising an ash tank having a substantially flat bottom provided with a discharge opening, means 40 located adjacent the bottom of said tank for separating water from the ashes deposited on the bottom of said tank, and means located adjacent said opening for directing steam jets upwardly and away from said 45 opening.

2. An ash conveyer system comprising an ash tank having a substantially flat bottom provided with a discharge opening, and means adjacent said discharge opening for 50 projecting steam jets upwardly and away from said opening.

In witness whereof, I hereunto subscribe my name this 9th day of August, A. D. 1917.

TOWNER K. WEBSTER, JR.
